F. E. Mann,
Inventor

By *Clarus A. Bain*
Attorney

UNITED STATES PATENT OFFICE.

FREDERICK E. MANN, OF CHERRYDALE, VIRGINIA.

CRYSTAL DETECTOR.

Application filed December 10, 1923. Serial No. 679,692.

To all whom it may concern:

Be it known that I, FREDERICK E. MANN, a citizen of the United States, residing at Cherrydale, in the county of Arlington and State of Virginia, have invented certain new and useful Improvements in Crystal Detectors, of which the following is a specification.

This invention relates generally to radio telephony and has specific reference to the crystal detectors employed in conjunction with certain types of radio sets.

The primary object of the present invention is to provide a crystal detector, broadly of the type shown and described in my co-pending application, Serial Number 675,676, wherein the same may be mounted within a radio set cabinet for imparting thereto the appearance of a radio set of the tube or higher priced type.

An additional object of the invention is to provide a crystal detector to be mounted within a cabinet, wherein the spring contact, or "cat whisker" as well as the crystal elements may be moved toward or away from each other, by means externally of the cabinet, and wherein extremely fine adjustments of the crystal elements may be obtained for thereby effecting a very sensitive tuning of the radio apparatus with which the detector is associated.

Yet another object is to provide in combination with the detector, means for allowing a clear vision to be had of the adjustments of the spring contact and crystal elements with respect to each other, for thereby obtaining the proper tuning effect of the radio apparatus in a minimum amount of time.

With the above and other objects in view as the nature of the invention will be better understood, the same comprises the novel form, combination and arrangement of parts hereinafter more fully described, shown in the accompanying drawing and claimed.

In the drawing wherein like reference characters indicate corresponding parts throughout Figures 1 and 2, and wherein there is disclosed the preferred and a slightly modified form of the present invention,

Figure 1 is a fragmentary front elevational view of a radio receiving set cabinet upon the interior of which is disposed a crystal detector constructed in accordance with the present invention.

Figure 2 is a similar view of the interior of the cabinet for disclosing more clearly the relative positioning of the present crystal detector upon the back side of the front panel board of said cabinet, and

Figure 3 is a longitudinal sectional view through said panel board, the crystal detector in this instance being provided with a modified means for adjusting the spring contact or "cat whisker" with respect to the crystal contact element.

Now having particular reference to Figures 1 and 2 of the drawing, there is shown a crystal detector adapted for disposition within the cabinet of a radio set that is constructed generally in a manner similar to the detector shown in the above mentioned co-pending application. That is, the device includes the spring strip 10 upon the top side of which is disposed the holder 11 for the crystal carrying cup 12 and that carries at one end a vertical post 16 within the slotted upper end of which is pivotally disposed the arm 17 formed at its other end with a ball-shaped head. As in my co-pending application this head is disposed between the adjacent ends of a pair of spaced parallel plates 20, the same being formed at this end with segmental spherical openings for this purpose and for establishing a universal connection between the plates and arm. Disposed for universal movement between the other ends of the plate is the stem 22 that carries at its lower end the spring contact or "cat whisker" 24 and at its upper end the finger piece or knob 23.

In the present instance, the post carrying end of the spring strip 10 is secured to and insulated from an inverted L-shaped bracket 25 secured as at 26 to the inner side of the front panel board 27 of a radio receiving set cabinet, and this slightly beneath and at one side of a vertically arranged oblong opening 28 in said panel bars.

It will thus be seen that the crystal element as well as the spring contact will be positioned within the cabinet at a point directly rearwardly of the opening 28, wherefore in the movements thereof with respect to each other may be clearly viewed, it being also noted that the finger piece or knob 23 is extended outwardly through the opening for allowing the spring contact to be readily moved into engagement with and over the face of the crystal element.

For allowing the spring and crystal contact elements to be more clearly viewed by the operator of the set a suitable form of reflector 29 is disposed within the cabinet and at a point directly behind said spring and crystal element.

Disposed for free rotation through an opening in the panel board 27 at a point directly beneath the free end of the spring strip 10 is a shaft 30 upon the inner end of which is eccentrically disposed a disk 31 the periphery of which is always engaged by the free end of the spring strip 10 due to the fact that the tendency of the spring strip is to flex downwardly.

The outer end of the shaft is equipped with a desirable form of operating knob 32 whereby the shaft may be easily rotated in the desired direction.

It will thus be seen that after a rough adjustment of the spring contact with relation to the crystal has been obtained by moving the finger piece or knob 23 an extremely fine adjustment between the contacts may be procured by slowly moving the knob 32 in the desired direction the movement of said knob obviously causing relatively slight movements of the crystal elements.

In Figure 3 wherein the detector construction is identical with that shown in Figures 1 and 2 with the exception of the cat whisker carrying and adjusting mechanism, the front panel board 27' of the receiving set cabinet is provided upon the right hand side of the opening 28' therein with a circular shaped opening 33 within which is set a metal plug 34 that is formed with a central transverse opening that flares outwardly at its inner end and that terminates at its front end into a socket 35. Positioned within this socket 35 is a ball-shaped head 36 formed upon a rod 37, the outer end of which is equipped with a finger piece or knob 38 while the inner end thereof is inturned at 39 in a direction toward the opening 28' in the panel board 27' and to which is attached the spring contact or "cat whisker" not shown.

For maintaining the ball-shaped head 36 within the front socketed end of the opening of the plug 34 there is provided a retaining plate 40 secured to the front side of said plug 34 in any manner desirable. It will therefore be seen that I have provided in

this modified form of the invention, a highly novel and simplified form of universal support for the spring contact or cat whisker of the present crystal detector, and in this instance it will also be noted that said spring contact may be adjusted relative to the crystal by the hand of the operator and this without necessarily having to position the hand forwardly of the opening 28' in the panel board 27' which might otherwise mar the view of the contacts of the deflector.

From the foregoing it will be clearly apparent to those skilled in the art that I have provided an extremely simple and efficient form of crystal detector that may be positioned interiorly of a radio receiving set cabinet and wherein the spring and crystal contacts thereof may be adjusted with respect to each other by means externally of the cabinet.

Minor changes may be made in the invention without departing from the spirit and scope of the appended claims.

Having thus described my invention, what I claim as new and desire to secure by Letters-Patent, is:

1. A crystal detector comprising a panel having an opening formed therein, a supporting bracket mounted on the rear side of the panel and at one side of the opening, a shaft rotatably mounted in the panel at the opposite side of the opening, and projecting from opposite faces of the panel, a disc eccentrically mounted on said shaft in the rear of the panel, a spring strip secured at one end to the supporting bracket and having its opposite end engaging the periphery of the disc and normally tensioned in engagement therewith, a crystal element mounted on the strip in the rear of the opening in the panel, a spring contact movably mounted on said supporting bracket for engagement with any desired portion of the crystal, an operating means carried by said spring contact operable from in front of the panel for engaging said spring contact with the crystal, said shaft being manually rotatable from the front of the panel for moving said disc, so that the crystal may be adjusted to vary the tension of the spring contact thereon.

2. A crystal detector comprising a panel having an opening formed therein, a supporting bracket mounted on the rear side of the panel and, at one side of said opening, a spring strip mounted at one end on said bracket and projecting across the lower end of said opening in the panel, means operable from the front plate of the panel and mounted thereon for engaging and maintaining said spring strip under tension, and operable for raising and lowering the free end thereof, a crystal element mounted on the central portion of said spring strip in the rear of the opening in said panel, and

a contact spring movably mounted on said supporting bracket having means projecting beyond the front face of the panel so that the contact spring may be operated to engage the desired portion of the surface of the crystal element, said operating means being adapted to effect a movement

of the crystal toward or away from the contact spring to vary the tension of the spring on said crystal. 10

In testimony whereof I affix my signature.

FREDERICK E. MANN.
